UNITED STATES PATENT OFFICE.

CHARLES S. HERSH AND EDWIN F. WEAVER, OF PHILADELPHIA, PENNSYLVANIA, ASSIGNORS OF ONE-THIRD TO ALFRED E. CLARKE, OF SAME PLACE.

TROLLEY-WIRE CROSSING.

SPECIFICATION forming part of Letters Patent No. 534,605, dated February 19, 1895.

Application filed March 13, 1894. Serial No. 503,415. (No model.)

To all whom it may concern:

Be it known that we, CHARLES S. HERSH and EDWIN F. WEAVER, citizens of the United States, residing in the city and county of Philadelphia, State of Pennsylvania, have invented a new and useful Improvement in Trolley-Wire Crossings, which improvement is fully set forth in the following specification and accompanying drawings.

10 Our invention relates to electric power lines or circuits, upon which move electric contact brushes, trolleys or similar devices carried by a vehicle, and adapted to supply electrical energy thereto from the conductor, and 15 our object is to provide a novel construction of a trolley wire crossing, whereby one conductor crossing another may be employed without interference therewith.

A further object of our invention is to provide means for making the crossing device reversible, and to these ends our invention consists in a bridge having one of its trolley tracks pivoted to the frame thereof, so that 25 gravity or other means will maintain it in its normal position, as will be hereinafter set forth.

Figure 1 represents a side elevation of a trolley wire crossing embodying our invention. Fig. 2 represents a perspective view 30 on an enlarged scale of a portion of the same showing the reversible portion of the crossing device partly turned. Fig. 3 represents a section on line *x*, *x*, Fig. 1, on an enlarged scale. Fig. 4 represents a clamp used to hold 35 the trolley wire to the bridge. Fig. 5 represents a sectional view on line *y*, *y*, Fig. 4.

Similar letters of reference indicate corresponding parts in the several figures.

Referring to the drawings: A designates 40 the frame of the bridge having at the center a U-shaped recess in which is swiveled the U-shaped frame B, which is suspended in any suitable manner and can turn freely therein. In the present instance we have 45 shown the frame B swiveled on the bolt C, which has a head E and the nut D, said nut D resting in a recess F of the clamp G, to which recess the nut or head D may be applied and removed at the side of the clamp, 50 which latter has ridges similar to H, H, (Fig.

4) and which when bolted together hold the wire in place.

I designates clamps which are similar to the clamp G, with the exception of the recess F.

Between the upper end of the U-shaped frame B, and the head E of the bolt, is the bar K, to which the plate L is secured at each end by means of bolts M.

N designates non-conducting material, such as mica, interposed between the bar K and plate L, said bar and plate forming a frame B' which constitutes a sustaining device for the wire or conductor O.

O designates a wire or conductor which passes at substantially right angles through 65 the bridge A, and rests in a groove in the under side of said plate L.

P designates holes which are drilled through the plate L, and filled with lead or solder to assist in keeping the wire O in place.

The U-shaped frame B is jointed at Q and R, at which points depend the arms S and T, respectively, the arm T being recessed at U to receive the end of the swinging bridge piece V, which is pivoted to the arm S at U. This 75 bridge piece is of good conducting material, and is preferably pivoted on a suitable support in electrical connection with the conductor, of which it forms a continuation, which in the present instance is the wire W, and is 80 adapted to swing from a position where it will be out of the path of the trolley moving on the conductor O into a position where it will bridge the space below said conductor to allow the trolley X of the conductor W to 85 move upon it.

Especial attention is called to the fact that the top of the bridge A is unbroken so that there is no necessity for bending the upper conductor in the application of our device to 90 existing lines of wire, the conductor W being simply applied to the top of the bridge A, and clamped thereto.

When the U-shaped frame B is in its normal position, as in Fig. 1, it is held in place 95 by the latches Y. When the frame B is locked in the position shown in Fig. 1, the device is set for the trolleys of cars going in the direction of the arrow to pass over the bridge, the impingement of the trolley upon the piv- 100

oted arm causing it to move upward into the recess U, preparing a path for the contact device of such car by thus moving the bridge piece into bridging position, as shown in dotted lines in Fig. 1. For the sake of simplicity in the operation of these contact bridges by means of the trolley carried by the car, we mount them to swing in a vertical plane. At the back of the arm V we provide a recess 10 Z for it to swing into, in case it should be struck or forced backward by any object. If it is desired to run a car in a direction opposite to that indicated by the arrow, it is only necessary to unhook the latches Y, swing the 15 frame B around, lifting the jointed parts S and T over the conductor O, and then lock them in place by the latches Y. The position of parts V and T will be reversed from that shown in Fig. 1, the bridge piece V appearing 20 at the right and T at the left.

The operation is now apparent. The trolley of a car moving from left to right leaves the wire W, when it reaches the bridge, and striking the bridge piece V, closes the gap, as 25 shown in dotted lines, and after its passage the bridge piece falls, leaving the way open for the trolley of a car going in the opposite direction. In Fig. 2, the reversible frame B is shown in the act of being swung to a position opposite to that shown in Fig. 1, it being necessary of course to lift the hinged portions T and S in order for them to pass over the wire O, but we do not desire to limit ourselves to the exact form and operation of the 35 devices herein shown and described.

For underground purposes, the crossing device and parts are inverted so that the bridge-piece V is above, a suitable spring being employed to hold the same in open position, and 40 a spring may be employed to assist in lowering the arm V when the crossing is overhead.

Having thus described our invention, what we claim as new, and desire to secure by Letters Patent, is—

45 1. In a trolley wire crossing, a frame with an open base having an arm adapted to close said base, the section carrying said arm being reversible, substantially as described.

2. In a trolley wire crossing, a frame having 50 a section swiveled thereto, said section having pivoted legs, substantially as described.

3. In a trolley wire crossing, a frame having an open base, a bridge piece pivoted thereto, said frame being provided with a slot 55 in the rear of said bridge piece for substantially the purpose set forth.

4. In a trolley wire crossing, a bridge piece, a frame having legs pivoted thereto, and 60 means for locking said frame in position, substantially as described.

5. In a trolley crossing, a frame having an

unbroken top to which a wire is adapted to be clamped, said frame having an open base, and an arm adapted to automatically close 65 said base by the action of the advancing trolley, substantially as described.

6. In a trolley crossing, a bridge having an open base, a rotatable bridge piece supported in said open base, and a pivoted arm on said 70 bridge piece adapted to be engaged by a trolley, and normally standing in position to permit the trolley on a crossing conductor to pass without obstruction, substantially as described.

7. In combination, a bridge having an open base, a bolt swiveled in said bridge, carrying the frame B and bar K, to which is attached the part L adapted to carry the conductor O, substantially as described.

8. In combination, the bridge A having an unbroken top adapted to carry the wire W, which is held thereto by the clamp G, which carries a bolt supporting the frame B, said frame having swinging legs, substantially as 85 described.

9. In a trolley wire crossing, a bridge and a clamp adapted to hold a wire thereon, said clamp being adapted to sustain the frame B, the bolt connecting said parts having its head 90 or nut in a recess in said clamp, substantially as described.

10. In a trolley wire crossing, a clamp adapted to hold a wire to the crossing bridge, said clamp having a recess which receives 95 the head or nut of a bolt on which is swiveled the frames B and B', the parts being combined substantially as described.

11. In a trolley wire crossing, a clamp adapted to hold the same to the crossing 100 bridge, said clamp having a recess which receives the head or nut of a bolt on which bolt is swiveled the frame B' composed of the bar K, and plate L, substantially as described.

12. In a trolley wire crossing, the herein 105 described wire-supporting device consisting of the bar K to which is secured the plate L, which is adapted to be in contact with a wire, the whole being suitably supported, substantially as described.

13. In a trolley wire crossing, the herein 110 described supporting device, comprising the bar K, to which is secured the plate L, adapted to be in contact with a wire, said plate being provided with the perforations P, which hold 115 filling material therein for securing the wire, the whole being suitably supported, substantially as described.
